E. M. FULLERTON

SHOE LAST AND METHOD OF MAKING SAME

Filed Dec. 13, 1926

Inventor
Ernest M. Fullerton
by James F. Hodder
Attorney

UNITED STATES PATENT OFFICE.

ERNEST M. FULLERTON, OF STOUGHTON, MASSACHUSETTS.

SHOE LAST AND METHOD OF MAKING THE SAME.

Application filed December 13, 1928. Serial No. 154 410.

My present invention is a novel and improved last for use in the manufacture of boots and shoes, and is particularly intended to reenforce the heel portion, and to afford 5 a new and improved thimble construction therefor.

My present invention is applicable to existing lasts, and is equally important and valuable in block lasts, hinge lasts, or any 10 other type, and is directed particularly to the heel and thimble construction. Shoe lasts are necessarily made with a metal thimble fitted in the bored recess in the heel portion on which the last and the shoe made thereon 15 may be "jacked" during various processes performed in the manufacture of the shoe. A great many machine operations require that the last be fitted on a jack, which jack has a spindle over which the thimble is applied, 20 and onto which the thimble is fitted. During the successive shoe manufacturing operations, the last and thimble are subjected to considerable pressure, hammering, tension, and the like, and very great stresses and 25 strains are transmitted through the thimble and the heel portion of the last during such shoe making operation. Thus, in heel nailing, leveling, sole laying, etc., the wood of the heel portion is subjected to crushing strains which often loosen the thimble from 30 the last. Furthermore, the continual tempering and drying of the soles impart an alternate moisture and drying action on the wood which necessarily "gives and takes" 35 somewhat in the drying, and this will further tend to loosen the thimble from the last, and once the thimble becomes loose, it will drop out when the last and shoe are inverted to be applied to a jack. My present invention 40 is directed to obviate these prior difficulties, to retain the last and thimble firmly together and prevent looseness, and also with the added feature of strengthening and stiffening the heel portion of the last. In carrying 45 out my invention I provide a standard type of thimble, preferably flanged such, for example, as shown in the prior patent to F. E. Benton, 1,140,850, issued May 2, 1916. With a thimble, and preferably a flanged thimble 50 of the type of said patent, I may bore through the bottom of the same, and counterbore the last between the usual thimble bored recess and the bottom at the heel portion, and fit therein a bolt, or form the thimble with an 55 added stem, said stem or bolt extending

downwardly a sufficient length to receive a nut or headed bearing which, being set up tightly, holds and combines the heel portion of the wood of the last, strengthening the same, and also holds the thimble firmly in 60 the last, and prevents it from working loose or dropping out, and which may be adjusted to compensate for wear.

Further details, improvements and novel combinations will be hereinafter more fully 65 pointed out and claimed.

Referring to the drawings, illustrating a preferred embodiment of my invention,

Fig. 1 is a fragmentary longitudinal sectional view of the heel portion of a last 70 embodying my invention.

Fig. 2 is a side view of a thimble;

Fig. 3 is a side view of a tube utilized with the form shown in Figs. 1 and 2;

Fig. 4 is a side view of a modified form of 75 thimble, and

Fig. 5 is a fragmentary longitudinal sectional view of the heel portion of a last 80 embodying the structure of Fig. 4.

Referring to Fig. 1, the numeral 1 designates the heel portion of the last, having the usual bored recess 2 therein from the top or cone of the last downwardly a sufficient extent to receive the barrel 3 of a last thimble. Preferably this thimble is formed with 85 a flange 4 to bear on the top of the last, as is customary. Through the bottom of the thimble a suitable opening 5 is formed. In alinement with the recess 2 I form a continuing smaller, recess 7 extending downwardly adjacent to the last bottom, preferably, also, counterboring a recess 8 from the bottom inwardly. This continuing recess 7 is preferably of less diameter than that of the thimble recess 2 in order to afford bearing 90 shoulders 10 for the bottom of the thimble which, in addition to the flange 4, gives a firm seat for the thimble. In the recess 7 I fit a tube 12, through which tube 12 I apply a bolt 15 of proper diameter to snugly 95 fit therethrough, and with a head 16 to bear upon the inner bottom of the thimble. This bolt extends downwardly a sufficient extent into the counterbored recess 8 to receive a nut or head 17, the tube 12 being of appropriate length to fit snugly between the bottom of the recess and the counterbored recess 8 so that, when the nut 17 is set up tightly, the thimble, the bolt, and the tube 100 12 are in firm and solid engagement. There- 105 110

upon the usual heel clinching plate 20 is applied, thus covering and protecting the counterbored recess and the nut and bolt.

The construction just defined gives a firm, strong union, strengthening and reinforcing the entire heel, and tending to prevent the crushing of the wood at the heel during the shoe manufacturing processes. This binding at the heel portion has a substantially "truss-like" effect on the heel of the last, and besides effectually holds the thimble in all times, preventing it wearing loose and coming out. The nut 17 is also adjustable to compensate for wear, both in the wood and tube, which is an important feature. In the modification illustrated in Fig. 5 I have shown a special form of thimble having a barrel 20, the flange 21, and the integral extending portion 22 being substantially the equivalent of the bolt 15 in the form just described. This modified form of thimble thus carries its own bolt and extension, having the lower end of the same threaded, as at 23, to receive a correspondingly threaded nut 24 which is fitted thereon and which is also adjustable for wear. In this form I may apply the same to the last with or without a tube 12, and preferably, also, in this form of last I drill the thimbled recess out of solid stock, and mill down the stem 22. It will thus be seen that I have devised a novel,

simple, efficient, and improved last construction, as well as a method of holding in the thimble while strengthening the heel portion with the truss-like binding effect, and also have devised a novel form of thimble with an extension permitting such binding action, and I therefore claim such device herein broadly.

Having thus described my invention, what I claim as new is:

An improved last having a thimble recess and a recess of smaller diameter in alignment therewith, the last bottom having an enlarged counterbored opening in alignment with said smaller recess, a thimble having an opening through the bottom fitted in said thimble recess, a metallic tube of proportional length fitted in said smaller recess between the thimble recess and said counterbored opening, a bolt fitted through the tube and the opening in the thimble, and retaining means on each end of said bolt, one bearing on the thimble bottom and the other on said tube, one of said retaining means being removable and adjustable, in combination with a heel plate on the last bottom covering and protecting said counterbored recess.

In testimony whereof, I have signed my name to this specification.

ERNEST M. FULLERTON.
